UNITED STATES PATENT OFFICE.

SAMUEL R. PARKS, OF CENTRAL FALLS, RHODE ISLAND.

TROLLEY-POLE GUIDE-ROPE.

SPECIFICATION forming part of Letters Patent No. 613,713, dated November 8, 1898.

Application filed August 4, 1897. Serial No. 647,067. (No model.)

To all whom it may concern:

Be it known that I, SAMUEL R. PARKS, of Central Falls, in the county of Providence, in the State of Rhode Island, have invented certain new and useful Improvements in Guide-Ropes for Trolley-Cars; and I do hereby declare that the following, taken in connection with the drawings which accompany and form part of this specification, is a description of my invention sufficient to enable those skilled in the art to practice it.

My invention relates to the form and construction of the rope and its appendages used to control the trolley-pole of cars propelled by electricity.

Figure 1 of the accompanying drawings represents a section of a car, trolley-wheel, and pole, with my improved guide-rope attached to the pole. Fig. 2 is a modification of the rope represented by Fig. 1, the trolley-wheel, and section of the pole. Fig. 3 is a horizontal section of the funnel, taken through the line *m m* of Fig. 4. Fig. 4 is an enlarged longitudinal view of the guide-rope and funnel, shown in section, corresponding to Fig. 2; and Fig. 5 is an enlarged view of the guide-rope and funnel, both at the place of union, shown in section, which corresponds to that part of Fig. 1 which illustrates the same parts.

Similar letters of reference represent corresponding parts in all the figures.

The object of this invention is to divert from the ordinary course the oily filth that drips from the trolley-wheel and overhead wire in rainy weather onto the dangling rope, down which the greasy water runs, bespat-

tering passengers and car with filth. For this purpose the rope is constructed as a flexible tube, which becomes a conduit to receive and convey the oily grime to the lower end of the 40 rope below the body of the car. The interior or tubular part may be made of any water and oil proof substance.

Underneath the trolley-wheel *W* a funnel *A* is suspended from the trolley-pole *B*. The 45 tubular rope *C* is so connected to the funnel that the spout or outlet discharges the drippings that it gathers from the wheel and overhead wire into and through the tube within the rope instead of being free to follow down 50 the outside, as is the case in the use of the ordinary solid rope. A collar *D* encircles the pole adjacent to the rope attachment to prevent the grime from following down the trolley-pole. The funnel may be so placed as to 55 become an extension of the rope, as shown in Fig. 1, or it may be attached to the rope at any convenient distance below the pole, as shown in Fig. 2.

What I claim as new, and desire to secure 60 by Letters Patent, is—

1. A tubular rope with funnel attached as set forth, in combination with trolley wheel and pole of trolley-cars, substantially as specified.

2. The combination of a flexible tubular rope, funnel, trolley wheel and pole, substantially as specified.

SAMUEL R. PARKS.
